RAZOR BLADE SECURING DEVICE

Charles R. Bennett, Cleveland, Ohio

Application April 30, 1948, Serial No. 24,353

3 Claims. (Cl. 30—58)

1

This invention relates to razors, especially to the razor blade securing means of a razor.

The present application is a continuation in part of application, Serial Number 685,841, filed July 24, 1946, upon a Razor, now Patent Number 2,575,539, dated November 20, 1951.

The general object of the present invention is to provide a novel, improved razor blade positioning head that is characterized by its positive engagement with a razor blade and with the easy release of the blade from the head.

A further object of the invention is to utilize an inexpensive spring member for retaining blade holding members together with a razor blade positively positioned therebetween.

A further object of the invention is to facilitate shaving action by the contour of the blade holding members and by removal of shaving soap and beard particles from engagement with the cutting portion of the razor blade.

Another object of the invention is to provide a spring for retaining razor blade holding means in engagement and to facilitate initial engagement of the spring with the razor blade holding means.

The foregoing and other objects and advantages of the invention will be made more apparent as this specification proceeds.

Attention is now directed to the accompanying drawing wherein Fig. 1 is an elevation, partially in section, of a razor using razor blade positioning devices embodying the principles of the invention;

Fig. 2 is a bottom plan of the razor blade securing device of the invention;

Fig. 3 is an end elevation of the device of Fig. 2;

Fig. 4 is a longitudinal section taken on line 4—4 of Fig. 3; and

Fig. 5 is an elevation taken on line 5—5 of Fig. 3.

With particular reference to the details of the structure shown in the accompanying drawing, a razor including a tubular handle 1 is shown and it is provided with a tubular end or top member 2 that engages with one end of the handle 1 by means of a friction joint. An end 3 is provided for the opposite end of the handle 1. The handle 1 has an axially directed slot 4 formed therein, which slot has a pin 5 extending therethrough and connecting to a block 7 that is positioned snugly in the handle for axial sliding movement therein. As more completely explained and claimed in the above-identified patent application, a razor blade securing device 100 is adapted to be supported by the handle 1. Also, the head

2

or device 100 is adapted to be received within the tubular handle 1. To this end, a pair of resilient arms 8 are secured to the block 7 and extend therefrom for engagement with the device 100. The pin 5 may be used for sliding the block 7 axially of the handle 1 for exposing or retracting the arms 8, as desired so that the razor unit of the invention can be operatively or inoperatively positioned.

10 The salient features of the present invention reside in the details of the razor blade positioning device 100, previously referred to. This device 100 includes a small, flat, rectangular member 11 which has hinge eyes 12 formed therein or suitably secured thereto. This member 11 also has a lip 13 extending therefrom substantially normal thereto. A second relatively small, substantially flat rectangular member 14 also is provided and it has a pair of hinge eyes 15 formed therein, one at each end of same. The members 11 and 14 are adapted to receive a hinge pintle 16 in the hinge eyes with the hinge eyes 12 being positioned immediately adjacent the inner ends of the hinge eyes 15 to secure the members 11 and 14 together for relative pivotable movement therebetween.

15 A mounting bracket or flange 18 is provided on and usually formed integrally with the member 14, which bracket extends substantially normally therefrom. This bracket 18 has a pin 19 extending therethrough substantially perpendicular thereto adjacent each end thereof. The pins 19 are adapted to engage with the spring arms 8 so as to position the device 100 on such arms 8 for use of the razor device. Normally one of such arms is permanently engaged with one pin 19 whereas the other spring arm would be temporarily engaged with the remaining pin 19 only when the razor device was operatively positioned.

20 As an important feature of the invention, a substantially arcuate leaf spring 101 is provided in the device 100 for resiliently urging the members 11 and 14 into engagement. The spring 101 has an aperture 102 formed therein adjacent one end thereof whereas a slot 103 is formed in the opposite end of the spring. The spring 101 is adapted to be compressed between the lip 13 and the bracket 18. Engagement of the spring with these members is facilitated due to the fact that the slot 103 may be engaged readily with its associated pin 19 after which the spring 101 can be slid into its operative position between the lip 13 and bracket 18, and the hole 102 can be snapped into engagement with its associated 25 pin 19.

Figs. 3 and 4 best show that a pair of longitudinal directed slots 104 are formed in the member 14 adjacent the cutting edge of razor blade 10 which is positioned between the members 11 and 14. Thus when in use, shaving cream, hair particles, etc., that collect adjacent the end of the blade 10 and are forced in between same and the member 14, can flow therefrom through the slot or slots 104 provided in the member 14. The retention of the blade 10 in a desired position on the member 14 is facilitated by the formation of end flanges 105 on the member 14. Retention of the razor blade 10 in a desired position also may be expedited by the provision of a lug 106 that extends outwardly from the surface of the member 14 and engages with a hole formed in the blade 10 and adapted to receive the lug 106 therein. Of course, the end flanges 105 and lug 106 may either or both be formed on the member 11, when desired. In operation, member 11 is normally that at the top of the razor so that a curved contact edge 107 is provided on the member 14 to facilitate sliding contact of the razor device 100 over the skin surface to be shaved.

When one desires to change the razor blade being used, all that is necessary to do is to grasp the handle and arms 8 and then depress the lip 13 with the thumb or finger. Depression of the lip 13 causes the members 11 and 14 to pivot apart and the razor 10 will either fall from, or it can be shaken from engagement with the device 100. Any razor blade positioned in the device 100 will be continuously and automatically retained therein by the locking action of the spring 101.

In some instances, it may be desirable to retain a supply of extra blades in the end cap 2. Hence, blades 110 are shown positioned therein.

The spring 101 is also adapted to facilitate release of a razor blade and relative movement of the members 11 and 14 since the pin 19 normally is spaced from the inner end of the slot 103. Hence the end of the spring 101 may move longitudinally as the spring is flattened by pivotal movement of the lip 13. Of course, the spring 101 may be engaged with the members 11 and 14 and pins 19 otherwise than as set forth herein, if desired.

From the foregoing, it will be seen that an inexpensive, sturdy razor blade securing device is provided by the invention and that a spring is used effectively and continuously to retain a razor blade in operative position in a razor blade positioning device.

While one complete embodiment of the invention has been disclosed herein, it will be appreciated that modification of this particular embodiment of the invention may be resorted to without departing from the scope of the invention as defined by the appended claims.

Having thus described my invention, what I claim is:

1. In a shaving device, a flat blade engaging member having a lip portion extending therefrom at an angle to the member, a second flat

blade engaging member, means pivotally securing said blade engaging members together, and spring means constantly compressed between said lip and said second blade engaging member to urge said members into blade engaging position, said spring means comprising a substantially arcuate leaf spring, both ends of which are associated with said second member and which spring is compressed against the said lip, one end of said spring being slotted inwardly from the margin thereof and having movable engagement with said second member to facilitate deflection of said leaf spring on relative movement between said members and engagement of said leaf spring with said members.

2. In a shaving device, a flat blade engaging member having a hinge eye formed on one side edge thereof and with a lip portion extending therefrom at an acute angle to the member, a second flat blade engaging member having a pair of spaced hinge eyes formed on one side edge thereof and a mounting bracket extending from one face thereof, a hinge pintle extending through said hinge eyes and pivotally securing said blade engaging members together with said bracket and lip in adjacent relation, spring means positioned between said lip and the brake on said second blade engaging member to urge said members into blade engaging position, and pin means secured to and extending from said mounting bracket adjacent the ends thereof, said spring means being a leaf spring engaged adjacent its ends with said pin means.

3. In a shaving device, a flat blade engaging member having a hinge eye formed on one side edge thereof and with a lip portion extending therefrom at an acute angle to the member, a second flat blade engaging member having a pair of spaced hinge eyes formed on one side edge thereof and a mounting bracket extending from one face thereof, a hinge pintle extending through said hinge eyes and pivotally securing said blade engaging members together with said bracket and lip in adjacent relation, spring means positioned between said lip and the brake on said second blade engaging member to urge said members into blade engaging position, and pin means secured to and extending from said mounting bracket adjacent the ends thereof, said spring means being a leaf spring engaged adjacent its ends with said pin means, said spring being axially slotted at one end for adjustable engagement with one of said pin means.

CHARLES R. BENNETT.
